UNITED STATES PATENT OFFICE.

ALFRED W. WAIN, OF DETROIT, MICHIGAN.

DESIGN FOR A LOW-WATER-ALARM COLUMN.

SPECIFICATION forming part of Design No. 25,650, dated June 16, 1896.

Application filed March 5, 1896. Serial No. 582,009. Term of patent 7 years.

To all whom it may concern:

Be it known that I, ALFRED W. WAIN, a citizen of the United States, residing at Detroit, county of Wayne, State of Michigan, have 5 invented and produced a new and original Design for a Low-Water-Alarm Column, of which the following is a full, clear, and exact description, reference being had to the accompanying drawings, which form a part of 10 this specification.

In the drawings, Figure 1 is a view in perspective looking toward the front of the column, and Fig. 2 is a view in perspective looking toward the rear thereof, these two views 15 being deemed necessary to fully illustrate my design.

The leading features of my design consist in a column having its case formed with a vertically-raised head toward the front thereof, and with a laterally-projecting arm of 20 curved outline, the contour of said arm being below that of the top of the raised head or front portion, when viewed in elevation, the case curving downward from the top of 25 the head to said arm, the lower and upper contour of the head being also of curved form, and the front face of the head being of elliptical outline.

A represents the raised head or front portion, and A' the laterally-projecting arm of 30 the case. The front face A² of the case is elliptical in its outline and ribbed, the outline of the raised head A being essentially of the same outline in cross-section. The contour of the vertically-raised head A as it descends to the contour of the lateral arm A' is 35 a curved outline, as indicated at a, the case from the top a' of the head descending in a curve to the top a² of the arm A'. The laterally-projecting arm A' is circular in its general contour.

The front face and adjacent portion of the head project outwardly in the form of a flange as shown.

What I claim as my invention is—

The design for a low-water-alarm column, 45 as shown and described.

In testimony whereof I sign this specification in the presence of two witnesses.

ALFRED W. WAIN.

Witnesses:

N. S. WRIGHT,
JOHN F. MILLER.
